CLAIM

I claim the ornamental design for an interactive walker, as shown and described.

DESCRIPTION

FIG. 1 is a top front perspective view of the interactive walker according to the new design.

FIG. 2 is a bottom front perspective view of the interactive walker shown in FIG. 1.

FIG. 3 is a top rear perspective view of the interactive walker shown in FIG. 1.

FIG. 4 is a bottom rear perspective view of the interactive walker shown in FIG. 1.

FIG. 5 is a front elevation view of the interactive walker shown in FIG. 1.

FIG. 6 is a rear elevation view of the interactive walker shown in FIG. 1.

FIG. 7 is a left side elevation view of the interactive walker shown in FIG. 1.

FIG. 8 is a right side elevation view of the interactive walker shown in FIG. 1.

FIG. 9 is a top plan view of the interactive walker shown in FIG. 1; and,

FIG. 10 is a bottom plan view of the interactive walker shown in FIG. 1.

The broken lines in the drawings illustrate portions of the interactive walker that form no part of the claimed design.

1 Claim, 10 Drawing Sheets
